UNITED STATES PATENT OFFICE

2,584,766

BOAT PROPULSION DEVICE

Douglas K. Warner, Sarasota, Fla.

Application December 22, 1945, Serial No. 636,917

1 Claim. (Cl. 115—42)

1

The object of this invention is to furnish a lower unit for a boat's outboard motor which will permit operation of the boat in shallow water, eliminate the possibility of striking the propeller on bottom or on floating objects, avoid cutting fish lines with the propeller, eliminate underwater gears and other items at present subject to rapid wear; and avoid the propeller tip losses, which are apt to be excessive on the very small propellers used with high speed outboard motors due to the excessive twist given the propeller wake.

Secondary objects are: to provide an air film between the water discharged by the propulsion unit and the surface of the water over which it is discharged, in order that it may flow away from the boat with less resistance and less mingling with the water which is at rest on the surface which would thereby tend to dam up the discharge jet; and to provide means for deflecting the jet for steering.

The device is intended primarily for use with an air cooled five cylinder two cycle motor equipped with a transmission permitting direct drive; or drive through epicyclic planetary gears of five and one half to one reduction, shown in application 337,688 now 2,410,471 dated November 5, 1946, and application 634,811, so that when trolling at four miles per hour the throttle may be wide open at low propeller speed on direct drive, and so that the engine may be speeded up one hundred times faster to give the power for faster return home, this being made possible by the gear reduction. If the device is to be used with conventional outboards a water pump would, of course, be provided, but because the new motor uses neither pump nor fan neither are shown here.

Fig. 1 is a sectional view of the lower unit of the outboard motor.

Fig. 2 is a front elevation of same, viewed from boat or the right side of Fig. 1.

Fig. 3 is a rear view; Fig. 4 a top view; and Fig. 5 a view of the device from beneath it.

The device is to be fitted to a boat with a transom 1 which slopes upwardly rearwardly, or is vertical. By flange 3 the elbow 4 is bolted to the boat's stern. Inside the elbow the propeller 5, is mounted on shaft 6, the latter being supported by bushing 7 and thrust rolling ball bearing 8 which, in turn, is held in place by torque tube 9. The bushing 7 is mounted at the bottom of tube 10 and rigidly fixed by a turbine bucket shaped arm having trailing edge 11 and leading edge 11A, said arm 11 extended to the port so as to reverse the flow from the blade 55 moving forwardly on the port side of the boat, as shown in section 12A, past the rudder 13, which is turned by shaft 14 so that the jet of water may be thrown to either side and thus steer the boat.

The inlet openings 15 are protected from driftwood by bars 16 and sides 17. The boat is pro-

2

vided with two keels 18 each terminating just ahead of the stern in front of the sides 17. The screws, or pins, 19 fasten these sides of the inlet to the bottom of the boat, and the joint 20 between boat and upper part of opening is packed to prevent leakage of air into the water stream. The sides 17 are carried rearward at the height shown by dotted line 21 until they blend with the enlarging diameter of the elbow. Between the sides and the front curved wall 30 of the elbow the space is left without a top so that air may pass down as shown by dotted arrows under wall 22 of elbow in the passage 23 and thence out through opening 24 behind step 25. This air passes under rear step 26 to form an air film between the water discharged from opening at 27 and the surface of the water on which the boat is riding so that the discharge stream may quickly spread out without building a wave 20 behind the boat.

The discharge opening 27 is of semicircular form, its top shown in dots 28 and the flat bottom at 29.

Having thus described my invention what I claim as new and wish to secure by Letters Patent is:

In a boat propulsion device including a housing and a screw propeller and a propeller shaft mounted therein wherein said housing is formed in the general configuration of an elbow in the same vertical plane of said housing and having a face sloping forwardly and upwardly, said housing extending rearwardly therefrom and thence bending rearwardly downwardly, the downwardly bent portion formed to provide a lesser cross sectional area than said entrance and terminating in a discharge opening, that improvement which comprises locating said propeller generally in said entrance with said shaft coaxially therewith and upwardly extended, whereby the turning of said shaft accelerates water rearwardly.

DOUGLAS K. WARNER.
